US00D824380S

(12) **United States Design Patent** (10) **Patent No.:** **US D824,380 S**
Lee (45) **Date of Patent:** **** Jul. 31, 2018**

(54) **CAR MOUNT FOR ELECTRONIC DEVICE**

- (71) Applicant: **Bum Joon Lee**, Seoul (KR)
(72) Inventor: **Bum Joon Lee**, Seoul (KR)
(73) Assignee: **SPIGEN KOREA CO., LTD.**, Seoul (KR)
(**) Term: **15 Years**
(21) Appl. No.: **29/590,749**
(22) Filed: **Jan. 12, 2017**

Related U.S. Application Data

CLAIM

The ornamental design for a car mount for electronic device, as shown and described.

DESCRIPTION

FIG. 1 is a front perspective view of a car mount for electronic device, showing my new design;
FIG. 2 is a rear perspective view thereof;
FIG. 3 is a front elevational view thereof;
FIG. 4 is a left side elevational view thereof;
FIG. 5 is a right side elevational view thereof;
FIG. 6 is a top plan view thereof;
FIG. 7 is a bottom plan view thereof;
FIG. 8 is a front perspective view thereof, shown in a first alternate configuration with the arm portion of the car mount for electronic device rotated for clarity of disclosure;
FIG. 9 is a front perspective view thereof, shown in a second alternate configuration with the arm portion of the car mount for electronic device rotated and extended for clarity of disclosure; and,
FIG. 10 is a front perspective view thereof, shown in a third alternate configuration with the arm portion of the car mount for electronic device extended for clarity of disclosure.
The broken lines illustrate portions of the magnetic mount for electronic device that form no part of the claimed design.
